(57) CLAIM

The ornamental design for a body of an agricultural work vehicle, substantially as shown and described.

DESCRIPTION

FIG. 1 is a top view of a body of an agricultural work vehicle;

FIG. 2 is a left side view of the body;

FIG. 3 is a right side view of the body;

FIG. 4 is a front view of the body; and,

FIG. 5 is a back view of the body.

Phantom lines, where utilized, are for illustrative purposes only and form no part of the claimed design.

1 Claim, 5 Drawing Sheets
